UNITED STATES PATENT OFFICE.

VOTAW S. DURBIN, OF ST. LOUIS, MISSOURI.

PERISCOPE-MOUNTING.

1,319,464.

Specification of Letters Patent.

Patented Oct. 21, 1919.

Application filed April 13, 1918, Serial No. 228,345. Renewed December 20, 1918. Serial No. 267,713.

To all whom it may concern:

Be it known that I, VOTAW S. DURBIN, a citizen of the United States, residing in the city of St. Louis and State of Missouri, have invented new and useful Improvements in Periscope-Mountings, of which the following is a specification.

This invention relates to submarines, and particularly to the mounting of their periscopes. The general object of the invention is to provide simple and efficient means for sealing a cylindrical body such as the periscope guide of a submarine where it passes through the deck of the ship, my special object being to provide for insuring a tight seal at this point in spite of the great hydrostatic pressure which the parts sustain when the submarine is at the maximum running depth below the surface. One of my objects has been to provide for increasing the effectiveness of the packing to correspond with the increased hydrostatic pressure.

The invention consists in the general combination of parts and features to be particularly described hereinafter all of which contribute to produce an efficient periscope mounting. A preferred embodiment of my invention will be particularly described in the following specification while the broad scope of my invention will be pointed out in the appended claims.

In the drawing:

Figure 1 is a cross section through the deck of the submarine and showing the arrangement of parts for packing the periscope guide; this view also illustrates apparatus which may be employed to enable the pressure of the packing to be maintained, or varied when desired,

Fig. 2 is a plan of the packing member and showing its relation to the packing sleeve which also constitutes a feature of my invention,

Fig. 3 is a plan of the packing sleeve,

Fig. 4 is a vertical cross section through the packing sleeve, and

Fig. 5 is a typical section upon an enlarged scale at the packing point.

Referring more particularly to the parts, 1 represents a deck of a submarine which is provided with an opening, 2, at which there is attached a periscope mounting or seat, said seat being in the form of a low pedestal 3 presenting a flat upper face 4 to which a casing is attached. This casing

comprises an upper bearing member 5 secured in any suitable manner, such as by means of suitable bolts 6, the lower portion of the bearing member 5 being formed into a shallow dome 7 above which an integral bearing sleeve 8 extends upwardly to form a bearing for the periscope guide 9. The lower end of the periscope guide 9 is mounted on a suitable ball bearing 10 which enables the guide to turn or swivel in the bearing member 5.

On the under side of the bearing member 5 and within the dome 7 I attach a lower member 11. The casing has an opening through it for the periscope guide, for which purpose the members 5 and 11 have bores 12 and 13 which fit neatly to the periphery of the periscope guide. The lower member 11 may be attached to the upper member 5 by suitable studs 14.

The member 5 is formed with an annular recess 15 and the lower member 11 is formed with a similar recess 16. These recesses come together in a juxtaposed relation, to form a packing chamber of substantially circular cross section which communicates with the opening or bores 12 and 13. Furthermore, I prefer to form the packing chamber so that it presents an inclined or curved face 17 (see Fig. 5) adjacent to the outer face of the periscope guide 9, and I provide a similar inclined or curved face 18 on the wall of the chamber on the under side (see Fig. 5).

The periscope guide 9 is also preferably formed with a shallow annular curved recess or groove 19 (see Fig. 1) and this groove lies opposite to the packing chamber.

Within the packing chamber I provide an inflatable packing member 20, which is preferably of continuous annular tubular form; when this packing member is in use it is inflated by a fluid under pressure so that the inner side of the packing member will exert pressure against the side of the periscope guide. Furthermore, the inner side of the packing member, that is to say, the side adjacent to the periscope guide is provided with means which will prevent the packing member from engaging the periscope guide, and which will permit the guide to swivel or rotate on its longitudinal axis without disturbing the packing member. This means may be in the form of a liner or annular sleeve 21 (see Fig. 3), and this sleeve is preferably substantially of crescent shape in

cross-section with the convex side 22 of the crescent disposed inwardly. This sleeve lies between the inner side of the packing member and the curved face of the groove 19. Furthermore the curvature of the groove 19 constitutes a continuation of the inclined or curved faces 17 and 18. When the packing is placed in position, the upper edge 23 of the sleeve 21 preferably extends over the face 17 so as to seal off the periscope guide effectively along the annular edge 24. In a similar manner, the lower edge 25 of the sleeve 21 preferably extends over the inclined or curved face 18 at the annular edge 26. The packing member 20 is preferably formed of rubber and may be constructed like the inner tube of an automobile tire.

As, the wall of the packing member is thin, and flexible, it might happen that under the relatively high internal pressure its wall might tend to be squeezed into and pinched in the annular cracks at the edges 24 and 26. However, this is effectively prevented by the edges 23 and 25 which overlap these points. The form of the juxtaposed recesses 15 and 16 is such that the crescent-shaped sleeve co-operates with it to form a substantially circular cavity or chamber for the packing member.

Such a packing member may be applied as described above and then inflated and closed, and it will then exert pressure against the side of the periscope. I prefer however, to provide permanently attached means for maintaining the pressure in the packing member and for varying this internal pressure intermittently; this enables the internal pressure to be increased when the submarine is running at the maximum depth. The capacity for varying the pressure is a most advantageous feature of my apparatus because it enables the pressure to be relieved when not necessary, and this reduces the chance of pinching and thereby rupturing the inflatable packing member. For this purpose I prefer to provide means for inflating the packing member through the wall of the casing, preferably by providing a port 27 in the lower member 11 through which an inflating nipple 28 passes outwardly so as to be accessible within the dome 7. In order to provide for leading a fluid under pressure to this point without interfering with the parts which are associated with the roller bearing 10, I prefer to drill a substantially horizontal duct 28 laterally through the upper wall of the pedestal 3 near and substantially parallel with the face 4, and I also drill upwardly from below to form a communicating duct 29. The nipple 28 is connected by a suitable connection, including an elbow 30 and a union 31, with a nipple 32 which is screwed into the outer end of the duct 28. In the

lower end of the duct 29 a small pipe 33 is screwed, which leads upwardly from a three-way cock 34 connected to a pipe line 35 leading from a reservoir, or preferably from a small fluid pump or air compressor 36. 70

In the pipe line 35 a pressure gage 37 is attached for indicating the pressure existing in the pipe line and within the packing member 20.

The three-way cock 34 may be of any suitable construction and provided with an operating handle or lever 38. In one position of the handle 38 the pipe line 35 communicates with the pipe 33 to permit the fluid medium under pressure to pass up to 80 the packing member. Or the handle may be moved from this position so as to cut off the flow of the pressure medium and permit communication between the pipe 33 and an outlet port 39 of the three-way cock. Hence 85 this organization of parts enables the pressure within the packing member to be regulated.

In practice, if desired any well known automatic regulating means may be employed, controlled by a hydrostatic pressure device, for controlling the compressor or pump 36 automatically, to increase the pressure in the packing member when the submarine dives to a greater depth than that 95 at which it is running. However, by way of illustration, I have indicated diagrammatically, simple apparatus for this purpose, consisting of an electric motor 40 having an operating circuit 41 including a source of 100 E. M. F. such as a storage battery 42, the said circuit being controlled intermittently at will by a switch 43.

When the switch 43 is closed, the motor will actuate the pump or compressor 36 and 105 force the fluid medium into the packing member.

On account of the nature of the surface of soft rubber such as I intend to employ for the wall of the packing member 20, it is evident that under pressure this material will develop a relatively high frictional resistance to movement, and hence it will be held in place in the packing chamber. Furthermore, the sleeve is preferably of soft rubber 110 but its outer concave face 44 should be of a nature which will enable it to co-operate with the inner side face of the packing member so as to develop a high frictional resistance. This overcomes any tendency of the 120 sleeve to swivel or turn in the packing member. On the other hand, the convex surface 22 is constructed or is of such a nature that it co-operates with the periscope guide to develop a relatively low frictional resistance 125 at its points of contact with the periscope guide, thereby insuring that the periscope guide will swivel or turn freely in the sleeve without tending to turn the sleeve in the packing member. This effect is preferably 130

increased by lubricating the surface 22 with any suitable lubricant such as graphite. In other words, the natural effect of the surfaces of contact between the sleeve 21 and the packing member is to prevent the rotation of the sleeve, whereas the surface 22 is constructed or prepared to facilitate slipping of the periscope guide within the sleeve. Hence the sleeve coöperates with the other parts to insure that the packing member 20 will be held substantially fixed in the packing chamber under the action of the internal pressure, though this pressure firmly presses the sleeve against the side of the periscope guide and seals it, preventing the entrance of any sea water.

It is understood that the embodiment of the invention described herein is only one of the many embodiments my invention may take, and I do not wish to be limited in the practice of my invention nor in my claims, to the particular embodiment set forth.

What I claim is:—

1. In apparatus for packing the periscope guide of a submarine, the combination of a casing consisting of two members surrounding the periscope guide, said members having juxtaposed annular recesses forming a packing chamber around the periscope guide, an inflatable annular packing member received in said packing chamber, means for inflating said packing member with a fluid under pressure, to press the inner side of the packing member toward the periscope guide, a pressure gage for indicating the pressure of the fluid in the packing member, and means connected to said packing member capable of operating intermittently, for actuating said inflating means to vary the pressure in the packing member to correspond with the depth of the submarine below the surface.

2. In apparatus for packing a periscope guide, the combination of a casing having an opening through which the guide passes, and having an annular recess communicating with said opening to form a packing chamber around the periscope guide, an inflatable annular packing member received in said packing chamber, means connected to said packing member for inflating said packing member with a fluid under pressure, said packing member having means on the side thereof for preventing said inflatable member from directly engaging the periscope guide, said means engaging with the periscope guide and operating to develop a relatively low frictional resistance, whereby the periscope guide may swivel freely within said packing member, the fluid pressure operating to maintain said packing member in a substantially fixed position within said packing chamber.

65 3. In apparatus for packing a periscope

guide, the combination of a casing having an opening through which the guide passes, and having an annular recess communicating with said opening to form a packing chamber around the periscope guide, an inflatable annular packing member received in said packing chamber, said casing having a port, means connected to said port for inflating said packing member with a fluid under pressure, and having a connection leading through said port to the interior of said packing member, said packing member having means on the side thereof for preventing said inflatable member from directly engaging the periscope guide, said means engaging with the periscope guide and operating to develop a relatively low frictional resistance, whereby the periscope guide may swivel freely within said packing member, the fluid pressure operating to maintain said packing member in a substantially fixed position within said packing chamber.

4. In apparatus for packing a movable cylindrical part, the combination of a casing consisting of two members having juxtaposed annular recesses forming a packing chamber around the cylindrical part, an inflatable annular packing member received in said packing chamber, inflating means for inflating said packing member with a fluid under pressure, and a sleeve of flexible material covering the inner face of said packing member, said sleeve having a contact face engaging the face of the movable member of a nature to coöperate with the movable member to develop a relatively low frictional resistance, said packing member having a contact face engaging the outer face of said sleeve of a nature to coöperate therewith to develop a relatively high frictional resistance, to hold said sleeve in a fixed relation with respect to said packing member.

5. In apparatus for packing the periscope guide of a submarine, the combination of a casing consisting of two members surrounding the periscope guide, said members having juxtaposed annular recesses forming a packing chamber around the periscope guide, an inflatable annular packing member received in said packing chamber, means for inflating said packing member with a fluid under pressure to press the inner side of the packing member toward the periscope guide, and an annular sleeve disposed between the inner side of the packing member and the side of the periscope guide, said sleeve covering the face of the wall of said chamber adjacent the periscope guide on the upper side to seal the same.

6. In apparatus of the class described, the combination of a rotatable periscope guide having an annular groove on the 130

outer face thereof, an upper member and a lower member surrounding the periscope guide and having juxtaposed annular recesses forming a packing chamber opposite 5 site said groove, an inflatable annular packing member received in said packing chamber, means for inflating said packing member with a fluid under pressure to press the inner side of the packing member 10 toward the periscope guide, and an annular sleeve disposed between the inner side of said packing member and the face of said groove and having its upper edge extending into the packing chamber and lying 15 against the upper face thereof adjacent to said groove.

7. In apparatus of the class described, the combination of a rotatable periscope guide having an annular curved groove on 20 the outer face thereof, an upper bearing member and a lower member surrounding the periscope guide, said members having juxtaposed annular recesses forming a packing chamber, with the wall of said 25 packing chamber having an inclined face adjacent the periscope guide, an inflatable annular packing member received in said

packing chamber to press the inner side of the packing member toward the periscope guide, and an annular sleeve disposed between the inner side of the packing member and the side of the periscope guide, said sleeve being of substantially crescent shape in cross-section, and having its inner and convex face disposed in said curved 35 groove with the upper edge of said sleeve projecting over and lying against the said inclined face of said packing chamber adjacent to said groove to seal off the said bearing member. 40

8. In apparatus for packing a rotatable cylindrical part, the combination of a casting consisting of two members having juxtaposed annular recesses forming a packing chamber of substantially circular cross- 45 section around the cylindrical part, and an inflatable tubular packing member received in said packing chamber and exerting pressure against the face of the cylindrical part. 50

In testimony whereof, I have hereunto set my hand.

VOTAW S. DURBIN.
